DIALKYLAMINOALKOXYPHENYLETHANOL ESTERS

Seymour L. Shapiro, Hastings on Hudson, Louis Freedman, Bronxville, and Harold Soloway, Yonkers, N.Y., assignors to U.S. Vitamin & Pharmaceutical Corporation, New York, N.Y., a corporation of Delaware

No Drawing. Application April 9, 1958
Serial No. 727,258

13 Claims. (Cl. 260—326.3)

This invention relates to aryl and arylalkyl esters of β -dialkylaminoalkoxy- α -phenylethanols. More specifically, this invention is concerned with compounds of the formula

wherein R₁ and R₂ are lower alkyl groups, and those structures wherein R₁ and R₂ are connected so that with the attached nitrogen there is formed heterocyclic secondary amino substituents such as pyrrolidino, piperidino, morpholino, hexamethylimino and the like, R₃ is hydrogen and methyl and R₄ is hydrogen, lower alkyl, lower alkoxy and halogen. In addition variants of this invention the R₄—C₆H₄—CO— group is replaced by the cinnamoyl group C₆H₅CH=CHCO. Y is an alkylene linking element containing 2-3 carbon atoms such as ethylene, propylene and trimethylene.

The compounds of this invention are particularly useful as anesthetics and the invention will be illustrated by description in connection with such use.

Our esters show a very large improvement in the therapeutic index over conventional anesthetics. Thus, we have raised the therapeutic index of 13 found for procaine in our test method to as much as 300-9400 for our compounds under comparable conditions. One feature of our compounds, therefore, is their relative freedom from toxicity coupled with unusual effectiveness in anesthetic

2

EVALUATION AS ANESTHETICS

The compounds of this invention were evaluated by the method of Chance and Lobstein, J. Pharmacol., 82, 203 (1944), for determining the median effective dose of 5 a local anesthetic when applied to the cornea of a guinea pig eye.

A known concentration of solution of the local anesthetic is applied to both eyes of a guinea pig and the eyes kept bathed with this solution for two minutes. The 10 eyes are then blotted to remove excess solution.

Five minutes later, the eyes are tested for the anesthetic effect. A horse hair mounted on a glass rod is used. The hair is pressed against the center of the cornea so that the hair is bent to about the same extent at each application. The hair is applied 10 times to each eye, and the process repeated 5 times for the test (total of 100 prods). The result is reported thus: 100 minus number of blinks=percent anesthesia.

Varying concentrations of the anesthetic agent are used 20 and the percent anesthesia is plotted against concentration. The results are expressed as the ED₅₀ in mg./ml. which is the quantity of compound per milliliter of solution required to effect 50% anesthesia as established from the plot of concentration vs. percent anesthesia.

25 The toxicity of the individual compounds was established by administration subcutaneously (s.c.) to mice, in terms of the minimum dose required to be lethal to mice and expressed as LD_{min.} in milligrams of compound per kilogram of mouse.

30 The therapeutic index was then calculated by dividing the LD_{min.} by the ED₅₀, the result being a single figure embracing the anesthetic effectiveness of the compound and its inherent toxicity.

35 The results are shown in Table I. It will be noted that the compounds show therapeutic indexes of 230-9400 as compared to the index of 13 found for procaine, the standard local anesthetic, in comparative tests.

Table I.—Anesthetic potency of esters of β -dialkylaminoethoxy- α -substituted phenylethanols

R ₁	R ₂	R ₃	R ₄	Y	ED ₅₀ mg./ml.	LD _{min.} mg./kg.	Therapeutic Index

* The esterifying group is cinnamoyl rather than benzoyl (this is the product of Example 6).

action. Thus, some of our esters exhibit toxicities as low as one fifth that of procaine. Coupled with this safety factor of decreased toxicity is the high potency as anesthetics, which in individual cases is 5-240 times that of procaine. This desirable combination of normally opposed properties will be more clearly reflected in the pharmacological studies reported in Table I.

The compounds of this invention are bases, and as such form salts with inorganic or organic acids, and the compounds are suitably used in the form of their salts with inorganic acids such as hydrochloric, hydrobromic, sulfuric and the like, and such organic acids as acetic acid, butyric acid, pantothenic acid, theophylline, penicillin and the like.

Salts of the esters are readily prepared by the usual technique, as for example, by neutralizing our esters which are bases, by hydrochloric, hydrobromic, phosphoric, sulfuric, succinic, acetic, or tartaric acid, and other non-toxic acid in a suitable solvent such as alcohol, water, ether or benzene. The salts form directly and are collected on a filter or recovered by evaporation.

Quaternary salts are prepared by reaction of the basic esters with such quaternizing agents as methyl iodide, methyl sulfate, methyl toluene-sulfonate, ethyl bromide, 10 benzyl bromide, allyl bromide and ethyl bromoacetate.

These compounds of this invention are racemic mixtures of the "dl" forms and the invention encompasses the individual "d" and "l" forms, separable by techniques familiar to those skilled in the art.

In the preparation of the compounds of this invention, β -dialkylamino-alkoxy- α -phenylethanols (I) are esterified by reaction with the appropriately substituted benzoyl chloride or cinnamoyl chloride in an organic solvent such as benzene, toluene, ether or acetonitrile which is inert to the reactants, and in the presence of an acid acceptor. The acid acceptor function can also be served by the dialkylaminoalkyl component of the reactant alcohol, or the resultant product which is a corresponding basic ester. The reaction proceeds satisfactorily in some instances at room temperature, whereas other esterifications are desirably conducted at the reflux temperature of the solvent.

The required amino alcohols (I) are prepared by condensation of dialkylaminoalkanols with styrene oxide, or 30 p -methylstyrene oxide in the presence of an alkali metal catalyst according to the following equation:

After a suitable reaction period under reflux, the amino alcohol (I) is separated. In the course of the reaction, non-basic high-boiling side products, as yet unidentified, are formed, and after the condensation is completed, the basic components are separated when necessary into an aqueous phase as their hydrochloride salts, the non-basic side products are extracted with ether, the aqueous phase is then made basic, extracted with ether, and the desired amino alcohol (I) obtained by fractional distillation.

much the same manner with the selection of starting materials required for the production of any particular desired specific compound. Temperatures where shown are in $^{\circ}$ C.

5 EXAMPLE 1.—2-(2-[N-METHYL-N-I-PROPYLAMINO]ETHOXY)-1-PHENYLETHANOL

Sodium, 0.1 g. (0.005 mole), was added in small portions to 46.8 g. (0.4 mole) of N-methyl-N-isopropylaminoethanol while stirring. After solution was complete, the temperature was raised to 80° and 24.0 g. (0.2 mole) of styrene oxide added over a period of 1.5 hours. Stirring was continued at this temperature for an additional 5 hours.

15 On distillation, 23.5 g. of N-methyl-N-isopropylaminoethanol was collected, boiling at 72° at 30 mm., followed by 28 g. (60%) of product distilling at 120–128° at 0.35 mm.

Analysis.—Calcd. for $C_{14}H_{23}NO_2$: C, 70.9; H, 9.8; N, 20 5.9. Found: C, 71.1; H, 9.4; N, 5.6.

A hydrochloride was prepared and recrystallized first from methyl ethyl ketone, then from isopropyl alcohol and isopropyl ether mixture, melting at 133–137°.

Analysis.—Calcd. for $C_{14}H_{24}ClNO_2$: C, 61.4; H, 8.8; 25 N, 5.1. Found: C, 61.1; H, 8.3; N, 5.4.

EXAMPLE 2.—2-(2-PYRROLIDINOETHOXY)-1-PHENYLETHANOL

Sodium, 0.25 g. (0.01 mole), was added in small portions to 92 g. (0.8 mole) of 2-pyrrolidinoethanol while stirring. After solution was complete, the mixture was heated to an internal temperature of 125° and 48 g. (0.4 mole) of styrene oxide added over 1.5 hours. Stirring was continued at this temperature for an additional 4 hours.

35 On distillation, 54.8 g. of 2-pyrrolidinoethanol were collected, boiling at 76° at 10 mm. Further distillation of the reaction mixture gave 23.0 g. (41%) of 2-(2-pyrrolidinoethoxy)-1-phenylethanol, boiling at 130–138° at 0.1 mm.

Analysis.—Calcd. for $C_{14}H_{21}NO_2$: C, 71.5; H, 9.0; N, 6.0. Found: C, 70.9; H, 8.5; N, 5.7.

A hydrochloride, prepared and recrystallized (methyl ethyl ketone), melted at 125–130°.

45 Analysis.—Calcd. for $C_{14}H_{22}ClNO_2$: C, 61.9; H, 8.2; N, 5.2. Found: C, 62.1; H, 8.3; N, 5.5.

EXAMPLE 3

In a similar manner the following alcohols were prepared and are herein characterized.

β -DIALKYLAMINOALKOXY- α -SUBSTITUTED PHENYL-ETHANOLS

R_1	R_2	R_3	Y	Formula	B.P. $^{\circ}$ C.	mm. Pressure

As more specifically illustrative of the preparation of the compounds contemplated by this invention, the following specific examples of the preparation of specific compounds contemplated by this invention will serve to exemplify the preparation of all compounds, since all of the several compounds contemplated will be prepared in

70 EXAMPLE 4.—2-(2-DIETHYLAMINOETHOXY)-1-PHENYLETHYL BENZOATE

To a refluxing solution of 4.2 g. (0.03 mole) of benzoyl chloride in 100 ml. of dry benzene was added 7.1 g. (0.03 mole) of 2-(2-diethylaminoethoxy)-1-phenylethanol over 15 minutes while stirring vigorously. Reflux

was continued with stirring for 2 hours, after which the solvent was removed at diminished pressure. The resulting heavy oil was taken up in 100 ml. of water, made basic with 40% aqueous sodium hydroxide and then extracted with five 20 ml. portions of ether. After combining the ether extracts, these were dried over anhydrous magnesium sulfate, then filtered and the solvent evaporated. Distillation of the residue gave 4.8 g. (47%) of product, boiling at 162-164° at 0.06 mm.

Analysis.—Calcd. for $C_{21}H_{27}NO_3$: C, 73.9; H, 8.0. Found: C, 74.1; H, 8.3.

EXAMPLE 5.—2-(2-DIETHYLAMINOETHOXY)-1-PHENYL-ETHYL P-METHOXYBENZOATE

2-(2-diethylaminoethoxy)-1-phenylethanol, 7.1 g. (0.03 mole), was dissolved in 50 ml. of acetonitrile and 5.6 g. (0.033 mole) of anisoyl chloride added. There was a slight rise in temperature. The reaction mixture was permitted to stand two days at room temperature. After removing the solvent at diminished pressure, the base was prepared as described in Example 4.

On distillation, 2.5 g. of 2-(2-diethylaminoethoxy)-1-phenylethanol was recovered, boiling at 132-134° at 0.4 mm., followed by 3.9 g. of product boiling at 200-210° at 0.8 mm. The latter was redistilled to give 2.0 g. boiling at 188-192° at 0.2 mm.

Analysis.—Calcd. for $C_{22}H_{29}NO_4$: C, 71.1; H, 7.9; N, 3.8. Found: C, 71.2; H, 7.8; N, 3.8.

EXAMPLE 6.—2-(2-DIETHYLAMINOETHOXY)-1-PHENYL-ETHYL CINNAMATE

2-(2-diethylaminoethyl)-1-phenylethyl cinnamate was prepared by the method used in Example 5, starting with 7.1 g. (0.03 mole) of 2-(2-diethylaminoethoxy)-1-phenylethanol, 5.5 g. of cinnamoyl chloride and 50 ml. of acetonitrile. After removal of solvent, the residue was taken up in water, washed with ether and then converted to the base as in Example 4. Distillation yielded a forerun of 2-(2-diethylaminoethoxy)-1-phenylethanol, boiling at 114-116° at 0.18 mm., and then the product was obtained boiling at 192-194° at 0.08 mm.

Analysis.—Calcd. for $C_{23}H_{29}NO_3$: C, 75.2; H, 8.0; N, 3.8. Found: C, 74.8; H, 7.9; N, 3.8.

*The compound was isolated as the hydrochloride, M.P. 187-190°.

The new compounds may be used as medicaments, for example, in the form of pharmaceutical preparations which contain the compounds in admixture with a pharmaceutical organic or inorganic solid or liquid carrier suitable for parenteral or topical administration. For making these preparations there are used substances which do not react with the new compound, for example, water, gelatine, lactose, starches, magnesium stearate, talc, vegetable oils, benzyl alcohols, gums, polyalkylene glycols, petroleum jelly, cholesterol or other carriers known for medicaments.

It is to be understood that it is intended to cover all changes and modifications of the examples of the invention herein chosen for the purpose of illustration which do not constitute departures from the spirit and scope of the invention.

We claim:

1. The basic ester of the formula

wherein R_1 and R_2 are members of the group consisting of lower alkyl groups having a carbon content C_1-C_4 and the structure wherein R_1 plus R_2 is tetramethylene, R_3 is a member of the group consisting of hydrogen and methyl, R_4 is a member of the group consisting of hydrogen, p-chloro, p-methyl, o-methoxy and p-methoxy.

2. The compound

3. The compound

4. The compound.

5. The compound

6. The compound

7. The process for preparing a basic ester of the formula

wherein R_1 and R_2 are members of the group consisting of lower alkyl groups having a carbon content C_1-C_4 and the structure wherein R_1 plus R_2 is tetramethylene, R_3 is a member of the group consisting of hydrogen and methyl, R_4 is a member of the group consisting of hydrogen, p-chloro, p-methyl, o-methoxy and p-methoxy which comprises condensing, in the presence of catalytic quantities of sodium, an amino alcohol of the formula $R_1R_2NCH_2CH_2OH$ with a styrene oxide of the formula

separating by fractional distillation the formed β -dialkyl-aminoalkoxy- α -phenylethanol of the formula

esterifying said phenylethanol with an aromatic acid chloride of the formula

and isolating said basic ester.

8. The amino alcohol of the formula

wherein R_1 and R_2 are members of the group consisting of lower alkyl groups having a carbon content C_1-C_4 and the structure wherein R_1 plus R_2 is tetramethylene and R_3 is a member of the group consisting of hydrogen and methyl.

9. The compound

10. The compound

11. The compound

12. The compound

13. The compound

UNITED STATES PATENT OFFICE
CERTIFICATE OF CORRECTION

March 15, 1960

Patent No. 2,928,845

Seymour L. Shapiro et al.

It is hereby certified that error appears in the printed specification of the above numbered patent requiring correction and that the said Letters Patent should read as corrected below.

Column 4, line 6, title of EXAMPLE 1, for "-N-I-PROPYL-AMINO" read -- N-i-PROPYLAMINO --; lines 54 to 57, the formula should appear as shown below instead of as in the patent:

column 6, lines 20 to 23, the left-hand portion of the formula should appear as shown below instead of as in the patent:

column 7, line 2, the bond originating from the para position of the top benzene ring should have a CH₃ group attached thereto; line 26, for the "R" substituent shown in the lower benzene ring read -- R₄ --.

Signed and sealed this 23rd day of August 1960.
